UNITED STATES PATENT OFFICE.

PAUL DANIEL, OF JAMAICA, NEW YORK, ASSIGNOR TO MOSES ELY, OF NEW YORK, N. Y., AND CHARLES FULLER, OF PORT WASHINGTON, NEW YORK.

PISTON FOR GAS-ENGINES.

1,115,176.

Specification of Letters Patent. Patented Oct. 27, 1914.

Original application filed June 11, 1912, Serial No. 702,963. Divided and this application filed January 29, 1912. Serial No. 744,886.

To all whom it may concern:

Be it known that I, PAUL DANIEL, a citizen of the Republic of France, residing at Jamaica, in the county of Queens and State of New York, have invented certain new and useful Improvements in Pistons for Gas-Engines; and I do hereby declare the following to be a full, clear, and exact description of the invention, such as will enable 10 others skilled in the art to which it appertains to make and use the same.

In the progress of the gas engine art the necessity for diminishing the weight of the engine is always recognized, particularly 15 in connection with its application to the automobile and aeroplane arts where every ounce of weight avoided is important. Above all is this saving found highly necessary in connection with the moving parts 20 and especially the pistons of gas engines and the like, since such parts are required to reciprocate with immense velocity, and the energy expended in stopping and starting them between strokes is very considerable. 25 At the same time, inasmuch as these parts are subjected to violent explosive shocks at rapid intervals, as well as to intensely high temperatures, much difficulty is encountered in diminishing their weight 30 without weakening the engine to a dangerous extent. A large proportion of the fatalities incident to aeroplane practice has been due to unsuccessful efforts to diminish weight while keeping within the margin of 35 safety.

My present invention has relation to a device whereby material diminution in the weight of the pistons of internal combustion engines may be attained, without any loss 40 of strength.

A further advantage of the invention lies in the ease of construction which it introduces.

The invention is illustrated in a preferred 45 form in the accompanying drawing which is a median longitudinal section of my piston as applied to a particular form of engine set forth and claimed in my pending application, Serial Number 702,963, filed June 11th 50 1912, of which this application is a division.

Each trunk piston comprises the usual thin-walled cylinder 10, which is provided with an improved double head having the

advantages of lightness and protection of steel parts from overheating. For these 55 purposes the piston head is constructed of a light interior plate 11, preferably dish shaped, and made of cast iron, preferably in one piece with the cylinder 10. This material is eminently fitted for withstanding the very high temperatures of the flanges engendered within the working cylinder during operation.

In order to supply the necessary strength for resisting the shocks of the explosions, 65 and to permit the plate or inner head 11 to be made relatively thin and light, I supply a strong light steel backing or bridge 12 preferably provided with a central boss 13 into which is screwed the bolt 14, which 70 secures the inner head to the bridge or backing. The backing 12 is preferably also made dish-shaped and is supplied with an external circular flange 15 having external threads, as shown, whereby the entire backing 75 may be screwed home within the cylindrical portion 10. This furnishes an extremely solid and reliable support or abutment for the bridge 12.

It is an important feature of the preferred 80 form of my invention that the thread on the flange 15 shall be cut in the direction opposite to that in which the thread is cut upon the bolt 14, that is to say either of these threads may be a "right hand" thread, 85 the other being a "left hand" thread.

It will be seen that by the use of a suitable lock nut for the bolt 14, the opposite cutting of the threads as above described prevents all possibility of the parts coming 90 loose under the influence of the shocks to which the piston is subjected. Various forms of lock nut may be used, and in the drawing I have shown a copper washer 16 surrounding the bolt 14 under its head and 95 acting as a sort of gasket to prevent leakage of gas from the working cylinder. This gasket or washer is prevented from turning by pins 17 fixed to the cylinder head and extending into the washer. The edges of 100 the washer can be bent up into appropriate recesses in the bolt head as shown at 18, to prevent the bolt from turning, all in a well known manner.

The backing 12 is provided with suitable 105 lugs 19, between which a connecting rod

20 is pivoted by means of the pintle 21. If desired, the backing 12 may be made lighter by cutting out at intervals, as shown at 22.

The piston herein described and claimed 5 may be used in various forms of engine, and either with stationary or revolving working cylinders, and various changes may be made in the same without departing from 10 the spirit of my invention. I do not limit myself to the details herein shown and described.

What I claim is—

1. In an internal combustion engine, a trunk piston having a compound head comprising 15 an inner plate of heat resisting material, and an arched reinforcing bridge of superior strength secured within the trunk piston behind said plate, substantially as described.

2. In an internal combustion engine, a 20 trunk piston comprising the usual cylindrical portion and having a compound head comprising an inner plate of heat resisting material, and an arched steel reinforcing bridge behind said plate secured at its periphery to the cylindrical portion of the 25 piston, substantially as described.

3. In an internal combustion engine, a 30 trunk piston having the usual cylindrical portion and provided with a compound head comprising an inner plate of the same material as the cylindrical portion, and an arched reinforcing steel bridge behind said plate, secured at its periphery to said cylindrical portion, substantially as described.

35 4. In an internal combustion engine, a trunk piston comprising the usual cylindrical portion and having a compound head, having a thin inner plate, and an arched reinforcing bridge screwed into the cylindrical portion and making contact with said inner plate near its center, substantially as 40 described.

5. In an internal combustion engine, a piston having a compound head comprising an inner plate, and an attached cylindrical 45 portion, in combination with an arched reinforcing bridge connected at its periphery with said cylindrical portion and making contact with said inner plate near its center, substantially as described. 50

6. In an internal combustion engine, a piston comprising an inner plate having a cylindrical portion, and a reinforcing bridge screwed into said cylindrical portion and connected to said inner plate by a central 55 screw bolt, substantially as described.

7. In an internal combustion engine, a piston having an internal plate provided with a cylindrical portion, and a reinforcing bridge screwed into said cylindrical portion and connected to said inner plate near the center thereof by the screw bolt, said screw bolt and the screw connection of said bridge with the cylindrical portion of the 60 piston having threads cut right and left respectively, substantially as described.

8. In an internal combustion engine, a trunk piston comprising the usual cylindrical portion and having an inner plate of cast iron to receive the pressure of explosion, in combination with an arched steel bridge making contact with the exterior side of said plate, to reinforce it, said bridge being suitably secured both to said cylindrical portion of the piston and to said 70 inner plate, substantially as described.

In testimony whereof, I affix my signature, in presence of two witnesses.

PAUL DANIEL.
